CLAIM

The ornamental design for a cookware packaging, as shown and described.

DESCRIPTION

FIG. 1 is an exploded view of cookware packaging showing our design;

FIG. 2 is a perspective view of a first component of a cookware packaging in an unassembled condition showing our design;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top view thereof;

FIG. 8 is a bottom view thereof;

FIG. 9 is a perspective view the cookware packaging of FIG. 1 in an assembled and closed condition;

FIG. 10 is a perspective view of the cookware packaging of FIG. 1 in an assembled and open condition;

FIG. 11 is a perspective view of a second component of a cookware packaging in an unassembled condition showing our design;

FIG. 12 is a front elevation view thereof;

FIG. 13 is a rear elevation view thereof;

FIG. 14 is a left side elevation view thereof, the right side elevation view being identical; and,

FIG. 15 is a top view thereof, the bottom view being identical.

The broken lines shown in the drawings are for the purpose of illustrating portions of the cookware packaging and environment which form no part of the claimed design.

(Continued)

Our Place is a registered trademark from Lagom Kitchen Company Corporation Delaware forming no part of the claimed design.
